UNITED STATES PATENT OFFICE.

CONRAD BERGMANN, OF PHILADELPHIA, PENNSYLVANIA, ASSIGNOR TO COLUMBIA STEEL EQUIPMENT COMPANY, OF PHILADELPHIA, PENNSYLVANIA, A CORPORATION OF PENNSYLVANIA.

CABINET.

Application filed March 9, 1925. Serial No. 14,227.

My invention relates to cabinets, and the principal object of the invention is to provide a novel and improved drawer mounting employing ball bearings instead of the usual 5 rollers.

The invention also resides in a novel and advantageous arrangement of tracks and in certain novel details of construction herein-after set forth.

10 In the attached drawings:

Figure 1 is a section on the line 1—1, Fig. 2, showing a cabinet with my improved drawer mounting, one side of the cabinet being removed to disclose the details of the 15 mounting;

Fig. 2 is an enlarged section on the line 2—2, Fig. 1;

Fig. 3 is a section similar to Fig. 1, but showing the drawer in the open position;

20 Fig. 4 is a sectional perspective showing one side and the bottom of the cabinet and the drawer supporting and guiding tracks and slides;

Fig. 5 is a view in perspective of one of 25 the supporting tracks which in assembly is attached to the sides of the cabinet;

Fig. 6 is a view in perspective of one of the intermediate or floating track members;

Fig. 7 is a view in perspective of one of 30 the slide members which in assembly is attached to the drawer;

Fig. 8 is a fragmentary perspective illustrating a modification within the scope of the invention, and

35 Fig. 9 is an end elevation of the parts shown in Fig. 8.

With reference to the drawings, the cabinet may comprise the usual open fronted rectangular casing 1 adapted to receive and 40 house a drawer 2, the latter having a front or face plate 3 adapted to close the aforesaid front opening of the cabinet, as illustrated in Fig. 1, when the drawer is closed. The cabinet in the present instance also comprises a floor 4 having at its edges elevated 45 portions 5 which at the sides form a support for longitudinal track members 6, 6, one of which is shown in perspective in Fig. 5.

These track members rest upon the elevated 50 portions 5 at the sides of the cabinet and are secured to brackets 7, 7, which latter extend longitudinally of the cabinet and are secured to the inner faces of the side walls thereof.

The general form of the track members 6 55 will be easily understood by reference to Fig. 5, which shows one of the track members in perspective. As therein shown, the track member comprises a vertical web 8 having at the top a substantially horizontal inwardly 60 projecting flange 9, the inner edge of which is turned inwardly to form a vertically depending flange 10. The web 8 also has at the bottom a substantially horizontal inwardly 65 projecting flange 11, the inner edge of which is turned upwardly to form the vertical flange 12. The horizontal flange 11 is ribbed at 13 to form a longitudinal channel 14 between the said rib and the web 8, this channel constituting a race for two ball 70 bearings 15 and 16, as shown in Fig. 5. The floor of the channel is provided with pressed-up points 17 which constitute stops for the balls and retain them within predetermined limits. Obviously, the nature of 75 the stops 17 may vary widely, and although in the present instance I have shown them in the form of pressed-up points in the sheet metal, they may be constituted in any other way that may be found desirable. Similarly, although the rib 13 is formed in the present instance by pressing up the metal of the flange 11, it is obvious that the race 14 may be formed in other ways without departure 80 from the essential features of the invention. 85

A ball bearing is also carried in the channel formed by the flanges 9 and 10 and the upper portion of the web 8, this ball 18 being retained in place by reason of the pressed-in formation of the web 8 indicated 90 at 19 in Fig. 5. The ball 18 is confined between two stops 20, 20, formed in the present instance by pressing in, at the two points, the metal of the web 8. The track 6 also carries at its forward end a stop 21 shown 95 in Fig. 1, the function of which will be described hereinafter.

It will be understood that two of the tracks 6 are employed, in construction the same except that one is left-handed and the other right-handed for attachment to the opposite sides of the casing.

In each of the track or support members 6 is an intermediate or floating slide 22, one of which is shown in perspective in Fig. 6, this being the floating slide or track member which is adapted to occupy the track member 6 shown in Fig. 5. As illustrated, this

floating member 22 is constructed more or less similarly to the track member 6, having a vertical back web 23, horizontal upper and depending vertical flanges 24 and 25, a horizontal lower flange 26, and the lower vertical flange 27.

As well illustrated in Fig. 2, the track member 22 is adapted to rest and slide within the fixed supporting track 6 with the lower horizontal flange 26 resting upon the balls 15 and 16 and the upper horizontal flange 24 resting under the ball 18. This ball 18, as shown in Fig. 1, lies behind a central upwardly extending lug 28 upon the floating track 22, which lug is adapted to engage the stop 21 on the fixed track 6 to limit the forward or outward movement of the floating track member 22 in the fixed track 6.

In the advanced position of the floating track member illustrated in Fig. 3, it will be noted that the inner end of the said floating track 22 lies outwardly of the rear stop 20 which limits the travel of the ball 18. In order to insure that the ball 18 may at all times occupy a position between the fixed track 6 and the floating track 22, the rear end of the flange 24 is inclined upwardly, as shown in Fig. 6, and is indicated at 29. This upwardly projecting portion of the track 22 will, if the conditions demand, engage the ball 18 and prevent it from passing backwardly over the rear end of the track 22.

At the front of the track member 22 and within the channel formed by the bottom horizontal flange 26, the vertical flange 27 and the web 23, is a ball bearing 30 which is permitted to travel in the channel between a stop 31 formed in the manner previously described and a stop element 32 shown best in Fig. 6, which is secured to the horizontal flange 26 at the extreme front of the track 22 and which projects downwardly and inwardly of the track in a stirrup formation. This stop 32 is so formed as to travel in the channel of the fixed track 6 formed between the flange 12 and the rib 13, but is of such length that the upturned end 33 thereof projects beyond the flange 12, and the forward end of the flange 12, as shown in Fig. 5, is cut away to permit the complete telescoping of the floating track 22 in the fixed track 6. The projecting end 33 of the stop member 32 performs a function hereinafter set forth. The flange 27 of the floating track 22 is recessed approximately at the center of the track, as indicated at 34, and this recess, when the floating track member is assembled in the fixed track 6, forms with the flange 12 a pocket for a ball 35, the latter resting upon the horizontal flange 11 of the track 6 and moving with the floating track 22 in its movement. The horizontal flange 26 of the floating track 22 is inclined down-

wardly at the rear, and this downwardly projecting end portion 36 will, in the event of the rear end of the floating track 22 passing beyond the rear stop 17 on the fixed track 6, engage the ball 16, and will prevent the ball from passing beyond the rear end of the floating track 22. The floating track 22 also comprises at the inner side of the vertical web 23 and just rear of the center, a longitudinal and inverted race 37 for a ball 38, this race being so formed as to normally retain the ball in spite of the inverted position.

The drawer 2 carries at each side a substantially horizontal outwardly projecting web or flange 39 formed in the present instance as the track member 40 shown in perspective in Fig. 7, which latter comprises a horizontal web 41 having at its inner edge a depending flange 42, and having at its outer edge an upwardly offset portion 43. The member 40 is secured, as clearly illustrated, to the bottom of the drawer 2, so that the bottom of the flange 41 normally bears upon the ball 35, while the offset portion 43 projects under the race 37 of the floating member 22 and engages the ball 38. The offset portion 43 of the track member 40 also is adapted to engage the ball 30 in the floating track member 22. The rear end of the offset portion 43 of this track member is turned up, as indicated at 44, and this turned up portion is adapted to engage the ball 38 in the race 37 and to prevent movement of the ball 38 past the rear end of the track 40.

The drawer 2 also carries on the under side and approximately at the mid section a pair of stops 45, 45, one at each side so placed that when the drawer is drawn out, as shown in Fig. 3, they will engage the upturned end 33 of the stop 32 on the floating track member 22, as shown in Fig. 3. In this manner and through the stops 32-45 and the stops 28-21, the outward movement of the drawer is limited, and in normal operation it is impossible to retract the drawer to such an extent that it will leave the tracks. The stops are so formed, however, as to permit removal of both the drawer and the intermediate track member by elevation of their forward ends.

It will be noted by reference to Fig. 3 that the drawer is adapted to move practically completely out of the cabinet, and that in this outward position, the floating track member 22, which assumes the position shown in Fig. 3, acts as a support for the drawer, preventing its tipping. The inner end of the drawer track 40 bearing against the ball 38 and the mid portion of the track member 40 resting upon the ball 30 prevents the drawer from tipping downwardly at the front when in the open position, and the floating track member 22 by bearing at the bottom against the balls 15 and 16, and at

the top against the ball 18 on the fixed track 6, is also held in position to support the drawer in the normal horizontal position. By reason of the contact between the ball 35 and the drawer track member 40, the outward movement of the drawer will tend to rotate the ball and roll it along its supporting track on the member 6, this forward movement of the ball carrying with it the intermediate or floating track member 22 which as the drawer is withdrawn accordingly progressively moves outwardly but at one-half the speed of the drawer, so that when the drawer reaches the outermost position, the intermediate or floating track 22 has been half withdrawn, as illustrated in Fig. 3. This progressive movement also takes place on the return of the drawer to the closed position, the track 22 moving progressively inward to the normal closed position shown in Fig. 1.

By use of ball bearings instead of the usual rollers the durability of the cabinet is considerably increased, since all journal pins are eliminated. In addition, the free movement of the ball bearings materially increases the freedom of movement of the drawer in the cabinet.

In Figs. 8 and 9, I have illustrated a modification within the scope of the invention in which instead of the ball 35 I employ a roller 46 journaled on a fixed pin 47 secured in the present instance to a plate 48 attached to the flange 27 of the floating track member 22. In all other respects, the construction is similar to that described above, and it has been found that with the roller 46 it is possible to obtain the desired progressive operation of the floating track member, as previously described.

Still further modifications are possible without departure from the essential features of the invention.

I claim:

A cabinet having a fixed track of channel form, said track having a rib extending longitudinally in the bottom thereof, telescoping tracks disposed in the channel of the fixed track in spaced relation thereto, balls for supporting the telescoping tracks relatively to each other, and balls mounted in the bottom of the channel on each side of the rib for supporting respectively the said telescoping tracks relatively to the said fixed tracks.

CONRAD BERGMANN.
